UNITED STATES PATENT OFFICE.

MILTON G. FORNIA, OF CARBONADO, WASHINGTON.

BABY WALKER OR EXERCISER.

Application filed January 24, 1921. Serial No. 439,522.

To all whom it may concern:

Be it known that I, MILTON G. FORNIA, a citizen of the United States, residing at Carbonado, in the county of Pierce and State of Washington, have invented certain new and useful Improvements in Baby Walkers or Exercisers, of which the following is a specification.

This invention relates to baby exercisers or walkers, of the type in which a support is provided for the child, so as to relieve the entire weight of the body of the child from its legs, in which free movement is given a child in a certain area and movement beyond the area prevented, whereby the likelihood of the child getting in dangerous places or near dangerous articles is eliminated, but at the same time permitting the child to have ample exercise to strengthen the leg muscles.

Another object of the invention is to provide a novel baby walker, which can be either used inside or outside of the house, embodying an adjustable seat for supporting the child, and a novel means for connecting the seat to an immovable support, the seat being mounted for free movement around the support.

A further object of the invention is to provide a baby walker and exerciser including a stationary supporting base, an outwardly extending arm mounted in the base for free rotary movement around the base, a supporting hoop for the child, an adjustable seat carried by the hoop, and means for associating a tray and sunshade with the hoop.

A further object of the invention is to provide a novel means for adjusting the height of the rotatable arm in relation to the ground on the support, and a novel means for adjusting the seat in relation to the supporting hoop.

A still further object of the invention is to provide an improved baby walker and exerciser of the above character, which is durable and efficient in use, one that is simple and easy to manufacture, and one which can be placed upon the market at a reasonable cost.

With these and other objects in view, the invention consists in the novel construction, arrangement and formation of parts as will be hereinafter more specifically described, claimed and illustrated in the accompanying drawings, in which:

Figure 1 is a perspective view of the im-

proved baby walker and exerciser, illustrating the type of base utilized for attachment to a floor.

Figure 2 is a fragmentary top plan view 60 of the hoop portion of the baby walker, parts thereof being shown in section.

Figure 3 is a fragmentary side elevation of the baby walker showing the hook portion thereof, and illustrating parts thereof 65 in section.

Figure 4 is a vertical sectional view 70 through the base portion of the baby walker, which is adapted to be attached to a floor,

Figure 5 is a vertical section through the base support, which is adapted to be utilized for insertion into the ground, when the baby walker is used in the open air.

Referring to the drawings in detail, 75 wherein similar reference characters designate corresponding parts throughout the several views, the letter A indicates the base of the baby walker and exerciser, which is adapted to be utilized for attaching the 80 walker to a floor; B, the base, utilized for insertion into the ground; C, the rotatable arm; D, the hoop carried by the rotatable arm; E, the seat supported by the hoop, and F, the tray detachably associated with the 85

The base A is adapted to be utilized for securing the baby walker to a floor, when the walker is used inside of a house or on a porch, and consists of a central bearing 10, 90 having a plurality of outwardly and downwardly extending legs 11 formed thereon. The lower terminals of these legs are provided with radially extending attaching feet 12, which are suitably apertured for the reception of retaining screws or the like 13. The screws 13 are adapted to be inserted into the floor or other support, as clearly shown in Figures 1 and 4 of the drawings. It is preferred that the upper edge of the bearing surface 10 be enlarged as at 14 for providing an enlarged bearing head, the purpose of which will be hereinafter more specifically described.

The arm C which is rotatably supported 105 within the base A includes the vertically disposed leg 15 and the radially extending right angularly disposed leg 16. The vertically disposed leg 15 is adapted to be placed in the bearing 10 for rotary movement, and the height of the radially extending or horizontally disposed leg 16 in re-

lation to the flooring or ground is regulated by means of a collar 17, which is slidably mounted upon the vertically disposed leg 15. This collar 17 is provided with a thumb screw 18, which is adapted to be adjusted into or out of engagement with the vertically disposed leg 15. The adjustable collar 17 forms a relatively large bearing surface for engaging the enlarged head 14 of the bearing sleeve 10, and it can be seen that by raising and lowering the sleeve or collar 17, the height of the horizontally disposed leg 16 in relation to the ground or support can be regulated. In order to brace the outer end of the horizontally disposed leg 16 to which the hoop D is attached, a diagonally extending brace or strut 20 is provided. This strut 20 is secured to the leg 15 at a point intermediate its ends, and to the outer end of the horizontally disposed leg 16, as at 21. The strut or diagonal brace 20 may have its terminals welded or otherwise suitably secured in place.

The hoop D in which the baby or child is to be inserted can be made out of any preferred material, such as iron, steel or wood, and is provided with a radially extending socket 22, in which the outer terminal of the horizontally disposed leg 16 is adapted to be inserted. The outer terminal of the diagonal strut or brace 20 is adapted to engage the outer face of the socket and forms additional support for the same. If so desired, the leg 16 and the strut 20 may be welded in place to the socket. The lower surface of the hoop D is provided at spaced points with depending eyes 24 which are adapted to receive the supporting straps 25 of the seat E.

The seat E includes a relatively broad body 26, provided with the forwardly reduced extending nose 27, and this seat E may be formed of any preferred material, either of leather, wood or metal. The forward end of the nose 27 has riveted or otherwise secured thereto one of the supporting straps 25, while the opposite sides of the body 26 has secured thereto the other supporting straps 25. These supporting straps 25 are inserted through the eyes, and a suitable buckle 28 is provided for each one of the straps so that the length thereof can be adjusted, whereby the height of the seat E in relation to the ground can be varied.

The tray F is arranged for detachable association with the hoop, and includes an arcuate body 30 having an outer arcuate flange 31. The inner end of the body 30 is provided at spaced points with depending pins 32, which are adapted to detachably fit in sockets 33 carried by the outer surface of the

hoop. At one side of the tray F, the hoop D has secured thereto a radially extending socket 34, which is adapted to receive the handle portion of a suitable sun shade, so that when the exerciser or walker is used out in the open air, an adequate protection may be provided for the child. An adjustable set screw 35 is provided for the socket, so as to frictionally hold the sun shade in place.

In use of the improved exerciser, the child is placed on the seat with its legs straddling the nose 27, and it can be seen that the child is free to move the hoop around the base A, and the falling down of the child is absolutely prevented, and thus accidents to the child are eliminated.

This type of walker has considerable advantage over the type which embodies wheels, so that the same can be pushed at any desired place, as in this type of walker the child is liable to run into dangerous positions, or hit obstructions where the walker is liable to be upset.

The walker, as described, can also be effectively used out in the open air, where the ordinary type of wheeled walker cannot be utilized, and when the type of walker described is used out in the open air, the base B is provided.

The base B includes a cylindrical relatively long sleeve 40 having a lower sharpened end 41, which is adapted to be inserted into the ground. The sleeve 40 is adapted to receive the vertically disposed leg 15 of the arm C, and the upper end of the sleeve is provided with an enlarged bearing head 42, for engagement with the bearing sleeve or collar 17.

Changes in details may be made without departing from the spirit or scope of this invention; but, I claim:

As a new article of manufacture, a baby walker comprising a base including a hollow socket, an L-shaped rotatable member, means adjustably and rotatably mounting the shorter leg of the L-shaped member in the socket of the base, a hoop, a radially extending socket formed on the periphery of the hoop arranged to receive the outer terminal of the longer leg of the L-shaped member, a seat adjustably carried by the hoop, and a diagonally extending strut secured to the shorter and longer leg of the L-shaped member, the outer end of this strut abutting the outer face of the socket and connected with the said longer leg at the outer end thereof whereby a suitable brace is formed for both legs of the L-shaped member and for the hoop.

MILTON G. FORNIA.
